DESIGN FOR A FINGER PULL FOR ZIPPERS
AND THE LIKE

Daniel I. Reiter, New York, N. Y.

Application June 16, 1947, Serial No. 139,709

Term of patent 14 years

(Cl. D17—8)

To all whom it may concern:

Be it known that I, Daniel I. Reiter, a citizen of the United States, residing at the Borough of Manhattan, city of New York, in the county of New York and State of New York, have invented a new, original, and ornamental Design for a Finger Pull for Zippers and the like, of which the following is a specification, reference being had to the accompanying drawing, forming part thereof.

In the drawings:

Fig. 1 is a front elevational view of a finger pull for zippers and the like showing my new design.

Fig. 2 is a side elevational view thereof.

Fig. 3 is an enlarged section of the finger pull for zippers and the like showing the design impressed thereon.

I claim:

The ornamental design for a finger pull for zippers and the like, substantially as shown.

DANIEL I. REITER.
